UNITED STATES PATENT OFFICE

2,330,909

DEVICE FOR DETERMINING THE CONTENTS
OF ROLLS OF OILCLOTHHerbert H. Olson, Los Angeles, Calif., assignor to
Columbus Coated Fabrics Corporation, Colum-
bus, Ohio, a corporation of Ohio

Application August 2, 1941, Serial No. 405,216

4 Claims. (Cl. 33—128)

The object of this invention is to provide a measuring device for rolls of textile material.

Heretofore in the art there have been many difficulties in determining the length of unwound textile material wound in the roll. One of the principal difficulties has been a means of easy and accurate reading of the contents of the roll without removing it from a shelf and without unwinding it.

Another object of this invention is to provide a readily readable, detachable measuring instrument for measuring the contents of a roll of textile material without unwinding it.

It is an object to provide such mechanism that can be readily mounted and demounted within the roll, that can be mounted on the roll while it is still in a rack or on a shelf and which will give a ready and substantially accurate indication of the contents of the roll.

My invention is particularly adaptable for the measuring of such materials as oilcloth. It gives a ready means of taking inventory. It is a further object to provide a combined transparent or translucent indicator and one that also reveals through the indicator disc the exact diameter of the roll.

It is an object to provide for the mounting of such indicator within the core upon which the oilcloth is wound without disturbing the winding of the oilcloth on the core.

Referring to the drawing:

Figure 1 is a perspective, partially broken away, showing the indicator about to be inserted in the core of a roll of oilcloth.

Figure 2 is a section of the line 2—2 of Figure 3 showing the position of the indicator when in its operative position with the hand of the operator compressing the roll of oilcloth to secure an accurate reading.

Figure 3 is a front elevation of the indicator and of the roll with the hand of the operator in position to hold the oilcloth so as to bring about an accurate reading.

Referring to the drawing in detail, I designates the disc of transparent plastic material in which are cut vertically disposed slots 2 on the opposite side of the center of the disc so as to permit the viewing of the oilcloth roll through the slot. The disc 1 is provided with a support 3 and the handle 4. Adjacent the slots are calibrations or measuring marks 5 having yardage indicating numerals 6 opposite each one of the lines.

The support 3 is inserted within the core 7 carrying the roll of oilcloth 8. The fingers 9 of

the hand of the operator are placed around the roll of oilcloth so that it can be compressed and brought into a reasonably compact condition. The edges of the oilcloth are then measured as to the total diameter of the roll according to their position with respect to the indicating line 5. This indicates the total yardage on the roll. These lines have been engraved upon the disc 1 as the result of the calibration of the disc.

It can be readily appreciated that by this very simple means it is possible to rapidly take an inventory of roll products, such as textile materials, oilcloth and the like. This measurement can be taken with the rolls on a shelf or in a rack without disturbing the roll or unwinding it. The oilcloth is visibly observed at the end of the roll through the slots 2 and a ready and effective means of reading the measurements is directly in front of the eyes of the user of this measuring device. By having the disc 1 of transparent material the end of the roll can be readily observed so as to be sure that the hand 9 of the operator in compressing the roll for reading has not distorted it out of its cylindrical condition to give a false reading. The pressure of the hand is just positioned to keep the roll in tightly wound condition for an accurate reading without distorting it.

One of the important features of the invention 30 is the ready means of inserting the support 3 for the indicator and the ready means of withdrawing it.

I desire to comprehend within my invention such modifications as may fairly fall within the scope of the following claims.

It will be understood that any type of textile material such as oilcloth or other types of yardage may be measured by this instrument.

It is further understood that this disc 1 may 40 be made of any material, but I prefer to make it of transparent material, particularly of plastic of the thermosetting type, or of the thermoplastic type, or of other materials of similar nature. The cylinder 3 acting as the fork in the handle 45 4 may be molded as one piece of the disc or may be made of separate materials.

The exact configuration of the margin of the disc 1 is not important although I prefer to have the body 1 made in a disc-like form as it aids the eye in negating the diameter of the yardage being measured.

Having thus fully described my invention what I claim as new and desire to secure by Letters Patent is:

1. A device for measuring yardage of material

wound on a core to form a roll comprising: positioning means insertable in the core of the roll; measuring means attached on one end of said positioning means; and indicia on said measuring means, said indicia being calibrated for direct reading of the yardage of material wound on the roll.

2. A device for measuring yardage of material wound on a hollow tubular core to form a roll comprising: positioning means insertable in the hollow tubular core of the roll said positioning means having a surface shaped to conform closely with the interior of said tubular core; disc or flange means attached on one end of said positioning means; and indicia on said disc or flange means comprising calibrations for direct reading of the yardage of material wound on the roll said measuring means adapted to lie closely adjacent to the side of the roll when said positioning means has been inserted in said hollow tubular core.

3. As a new article of manufacture, a device for measuring yardage of material wound on a hollow tubular core to form a roll, comprising a single disk or flange having indicia thereon comprising calibrations for direct reading of the

yardage of material wound on the roll, a cylindrical positioning means projecting centrally from one side of said flange and shaped to conform closely with the interior of said tubular core, a handle projecting from the other side of said disk or flange rigidly in line with said positioning means, said disk or flange adapted to lie closely adjacent to the side of the roll when said positioning means has been inserted in said hollow tubular core.

4. As a new article of manufacture for measuring yardage of material wound on a hollow tubular core to form a roll comprising a single disk or flange of transparent material having on its face indicia comprising calibrations for direct reading of the yardage wound on the roll, a cylindrical positioning device extending centrally rigidly from one side of said disk and shaped to fit the hollow tubular core of the roll, and a handle extending rigidly in line with said positioning device from the opposite face of the disk, said disk adapted to lie closely adjacent to the side of the roll when its positioning device has been inserted in said hollow tubular core.
